UNITED STATES PATENT OFFICE.

JOSEPH H. HAVILAND AND TRUMAN A. MITCHELL, OF WEEDSPORT, NEW YORK.

BUTTON-HOLE STRIP.

SPECIFICATION forming part of Letters Patent No. 433,863, dated August 5, 1890.

Application filed December 23, 1889. Serial No. 334,756. (No model.)

To all whom it may concern:

Be it known that we, JOSEPH H. HAVILAND and TRUMAN A. MITCHELL, citizens of the United States, residing at Weedsport, in the 5 county of Cayuga and State of New York, have invented new and useful Improvements in Button-Hole Strips, of which the following is a specification.

This invention has for its object to provide 10 a novel, simple, durable, and economical button-hole strip for attachment to articles of wearing-apparel, such as corsets, waists, and heavy garments.

The invention also has for its object to improve, strengthen, and render more durable 15 that type of button-hole strips wherein a cord is bent into loops and secured to a base-piece, so that the loops project at intervals and form the button-holes.

20 To accomplish these objects our invention consists in the features of construction and the combination or arrangement of parts, hereinafter described in detail, and specifically set forth in the claims, reference being 25 made to the accompanying drawings, in which—

Figure 1 is a broken perspective view showing a portion of our improved button-hole strip. Fig. 2 is a detail perspective view of 30 the looped cord, the longitudinal flexible stay, and the attaching-tabs; and Fig. 3 is a transverse sectional view of the complete button-hole strip.

In order to enable those skilled in the art 35 to make and use our invention, we will now describe the same in detail, referring to the drawings, where the numerals 1 and 2 indicate the inner and outer plies of what we term a “base-piece,” that can be formed with or be 40 attached to a corset, waist, or other garment.

The button-holes are formed by an inelastic braided cord bent at intervals into loops 3, with the longitudinal portions 4 embraced by tabs 5, each composed of a piece of textile 45 material folded upon itself, with a longitudinal portion 4 of the cord arranged between the folded parts along the folding-line. The tabs 5 are placed between the inner and outer plies 1 and 2 of the base-piece, and the whole 50 united by lines of stitches 6 and 7, thereby

leaving the button-holes projecting laterally in the form of loops. A longitudinal flexible stay 8 extends continuously along the entire length of the button-hole strip through the outer extremities 9 of all the loops in such 55 manner that the straining pull thereupon when buttoned is in a measure distributed upon and resisted or borne by the stay, giving the article considerable strength and rendering it durable and efficient. It is desirable 60 to cover and conceal the longitudinal flexible stay, and also to retain it within the outer ends of the loops, through which the stay passes, and to accomplish these purposes we apply a longitudinal binding 10, composed, as 65 here shown, of a strip of textile or other material folded around the stay to inclose it and lie under and over the outer ends of the loops. The folded tabs 5 are coextensive in width with the longitudinal portions 4 of the looped 70 cord, for the purpose of strengthening the article and aiding to preserve the looped form of the cord. A tab 5, folded as described, embraces the cord between every pair of loops; but none of these tabs are exposed to view, 75 since they are stitched between and covered by the two plies of the base-piece.

The longitudinal flexible stay may be composed of any material which will fulfill the conditions required; but we have satisfactorily 80 made the stay of a core-piece 12 of whalebone, inclosed within a textile or similar casing 13, as shown in Fig. 1. We do not, however, confine ourselves to whalebone, although a resilient material is preferred. The 85 space between every pair of loops and the adjacent edges of the binding 10 and base-piece is unobstructed and open in contradistinction to being filled with separate pieces of textile material.

The open spaces and other features shown and described render our article very economical in construction, and provides for the desired flexibility of all the parts, which is so important to produce a satisfactory and 95 desirable button-hole strip.

Having thus described our invention, what we claim is—

1. A button-hole strip consisting of a base-piece, a cord connected thereto and bent at 100

intervals into loops, a longitudinal flexible stay extending continuously through the outer extremities of all the loops, and means for retaining the stay in the outer extremities of the loops, substantially as described.

2. A button-hole strip consisting of a base-piece, a cord connected thereto and bent at intervals into loops, a longitudinal flexible stay extending continuously through the outer extremities of all the loops, and a binding-strip lying under and over the loops, inclosing and concealing the longitudinal stay and retaining it in the outer extremities of the loops, substantially as described.

15 3. A button-hole strip consisting of a base-piece, a cord connected thereto and bent at intervals into loops, a longitudinal flexible stay composed of a core incased by a covering of fabric and extending continuously through the outer extremities of all the loops, and a binding-strip lying under and over the loops inclosing and concealing the stay

and retaining it in the outer extremities of the loops, substantially as described.

4. A button-hole strip consisting of two superimposed layers forming a base-piece, a cord bent at intervals into loops, an independent tab located between each pair of loops and composed of a strip of material folded on itself, embracing the cord between said pair of loops and having its two extremities interposed between the two layers of the base-piece, and a continuous connection between the outer extremities of the loops to preserve them in proper position for buttoning, substantially as described.

25 30 35 In testimony whereof we have affixed our signatures in presence of two witnesses.

JOSEPH H. HAVILAND.
TRUMAN A. MITCHELL.
